UNITED STATES PATENT OFFICE

2,533,851

TOOL

Stanley Albert Temple, Lakewood, Ohio, assignor,
by mesne assignments, to Portable Industries,
Inc., Cleveland, Ohio, a corporation of Ohio

Application July 11, 1947, Serial No. 760,217

10 Claims. (Cl. 1-47)

1

This invention relates to improvements in tools. It has to do more particularly with tools of the type used for firing projectiles into metal, concrete or the like, the projectiles being of special form such for example as shown in my copending application Serial No. 624,935, filed July 19, 1946, and employed as fastenings in building construction.

One of the objects of the invention is the provision of a tool of the character stated which will present no hazard of accidental discharge and which shall automatically assume the safety position.

Another object is the provision of a tool of simple form and few parts that may be loaded quickly and that is rugged and certain in its action.

Still another object is the provision of means for absorbing recoil.

Other objects and features of novelty will appear as I proceed with the description of that form of the invention which, for the purposes of the present application, I have illustrated in the accompanying drawing, in which

Fig. 1 is a longitudinal sectional view of a tool embodying the invention, the view being taken substantially along the line 1-1 of Fig. 2;

Fig. 2 is a fragmental elevational view looking in the direction of arrow 2, Fig. 1; and

Fig. 3 is a cross-sectional view taken substantially on the line 3-3 of Fig. 1.

In the drawing 10 represents an elongated housing which may be cylindrical in shape, open at its front end and preferably closed at its rear end as shown. It may be formed of aluminum or other light metal or alloy if desired. A cylindrical carrier 11 is slidably mounted in the housing, being guided throughout most of its travel by a longitudinal slot 12 in the housing into which the head of a peg 13 extends, the shank of the peg being threaded into a tapped hole in the carrier 11.

A partition or other abutment 14 is secured within the housing at an intermediate point by screws 15 or other suitable means. It serves as an abutment for the rear end of a large resilient coil spring 16, the other or front end of the spring bearing against the rear end of the carrier. A barrel 17 is removably mounted in the carrier, preferably by means of a short coarse thread 18 formed at a point about two-thirds of the way down the barrel and engaging with a complementary thread at the front extremity of the carrier. That portion of the barrel which projects beyond the carrier may be knurled in

2

order to form a good grip for the operator's fingers when screwing the barrel into or out of the carrier. Preferably I use a thread of one and one-half turns which enables an operator to thread the barrel home by a single spinning movement thereof. The major portion of the barrel is thus surrounded and reinforced by the carrier 11 and also by the housing 10.

Barrel 17 has a bore 19 throughout the major portion of its length and a counterbore 20 at its rear end, the counterbore being adapted to receive a breech plug 21 that is formed alike at its two ends so that it may receive a blank cartridge 22 regardless of which end of the plug is inserted first. The front end of the plug bears against a thin flange 23 on the head of a projectile 24, here shown as a pin-like member with a rear head portion having a guiding fit in the barrel bore 19 and when the cartridge is exploded, force builds up until it becomes sufficient to shear off the flange and drive the projectile out of the tool with great force. A pair of diametrically opposed prongs 17' are formed at the extremity of the barrel for a purpose which will presently appear.

A firing pin 25 is slidably mounted in the carrier 11. It has a collar 26 that is engaged by a coil spring 27 to hold the pin in inoperative position, a hollow nut 28 threaded into the carrier 11 serving as a removable stop against rearward movement of the pin.

Abutment 14 is provided with a central aperture through which a plunger 33 is adapted to slide. A disk 31 is attached to, and in effect constitutes a part of, the plunger. A coil spring 32 bearing at one end against abutment 14 and at the other against disk 31 tends to hold the plunger in the retracted position illustrated in the drawing.

On the outside of the housing a sleeve 35, constituting a hand hold, is slidably mounted on the housing 10. It is attached to the plunger by means of screws 36 mounted in the sleeve, extending through slots 37 in the housing and threaded into the disk 31. The sleeve is thus nonrotatably slidable upon the housing. Part at least of the exterior surface of the sleeve is knurled as shown in order to provide a firm grip for the operator's hands.

Spring 16, being softer than spring 32, compresses when the operator pushes forwardly on the sleeve 35, the housing thereby moving forwardly around the barrel until it contacts the work, that is a wall, floor or ceiling into which the projectile is to be driven. Then since the

housing can go no further the spring 32 is compressed by further pressure exerted by the operator upon the sleeve 35, enabling the plunger 30 to strike the firing pin 25.

At its front end, slot 12 in the housing merges with a transverse cam slot 40, which in turn merges with the front end of a short longitudinal slot 41. The peg 13 is shown in the drawing in the position which it must assume at the beginning of a firing operation. Normally it stands at the front end of the short slot 41, since carrier 11 is impelled forwardly by spring 16 and angularly by the contact of peg 13 with cam slot 40. In this position relative longitudinal movement between the barrel or carrier and the housing will be limited by the short length of slot 41. For example if the tool should fall against a hard surface with the barrel front end down, the carrier would not be driven rearwardly or upwardly far enough to cause the firing pin to explode the cartridge.

Furthermore the tool cannot be discharged unless the front end of the barrel is held against a piece of work. For example if an operator should grasp the sleeve 35 in one hand and the housing 10 in the other and attempt to fire the tool he could not do so, for the travel of the sleeve relative to the housing is limited by the possible travel of screws 36 in slots 37 and this travel is less than the normal distance between the plunger 30 and the firing pin 25. In order to fire the tool, the front end of the barrel must be flush with the front end of the housing, and in addition the plunger 30 must be driven forwardly, and this can occur only when the front end of the tool barrel is against the work.

In order to overcome the automatic safety lock the barrel must be turned far enough to deflect the peg 13 out of the short slot 41 into the long slot 12. This the operator can do by grasping the projecting front end portion of the barrel with the fingers of one hand while turning the sleeve 35 with the other until the peg is in the long slot, but the prongs 17 facilitate the operation since they can be caused to bite into the work and thus hold the barrel stationary while the sleeve and housing are turned.

After the tool has been discharged the operator holds the sleeve 35 in one hand and the projecting end of the barrel with the fingers of the other hand, turns the barrel slightly to loosen the threads and then spins it to disengage the threads, after which he withdraws the barrel, removes the breech plug and the exploded cartridge, inserts a new projectile, puts a new cartridge in the breach plug and inserts the latter and then replaces the barrel and spins it to cause the thread 13 to lock it in position. The operation of removing the barrel and reloading it is thereby rapidly carried out.

Having thus described my invention, I claim:

1. In a tool of the character described, an elongated housing, a carrier in said housing, said housing and said carrier having limited longitudinal slidable movement relative to one another, a firing pin carried by said carrier, a barrel slidable in said housing and removably secured to said carrier, spring means for normally urging said carrier and said barrel toward the front end of said housing, the front end of said barrel being normally projected from the front end of said housing, a plunger in said housing for engagement with said firing pin, said plunger and said housing having limited longitudinal slidable movement relative to one another, spring

means for normally urging said plunger toward the rear end of said housing, said plunger and said firing pin being normally separated a greater distance than the extent to which said barrel is normally projected from the front end of said housing, with the result that there must be both relative longitudinal movement of said housing and said carrier and relative longitudinal movement of said housing and said plunger to bring

about engagement of said plunger and said firing pin, said two spring means being disposed on opposite sides of and bearing against a fixed abutment with which said housing is provided, and a hand hold sleeve slidably mounted on the outer surface of the rear end portion of said housing and to which said plunger is secured for movement therewith, whereby upon forward sliding movement of said hand hold sleeve, and with the projecting front end of the barrel against a fixed abutment, said plunger is moved toward the firing pin and the housing is moved forwardly relative to said carrier and said barrel.

2. In a tool of the character described, an elongated housing, a carrier slidable therein, said housing having two non-aligned longitudinal slots, one in advance of the other, and an intermediate cam slot joining said longitudinal slots, the two longitudinal slots being of different lengths and the one in advance being the shorter slot, a peg projecting from said carrier for movement in said slots, and spring means within said housing and normally urging said carrier forwardly relative to said housing, whereby said carrier peg is normally disposed in the shorter advanced slot.

3. In a tool of the character described, an elongated housing, a carrier slidable therein, a firing pin carried by said carrier, a plunger slidable in said housing for engagement with said firing pin, said housing having two non-aligned longitudinal slots, one in advance of the other, and an intermediate cam slot joining said longitudinal slots, the two longitudinal slots being of different lengths and the one in advance being the shorter slot, a peg projecting from said carrier for movement in said slots, and spring means within said housing and normally urging said carrier forwardly relative to said housing, whereby said carrier peg is normally disposed in the shorter advanced slot.

4. In a tool of the character described, an elongated housing, a carrier slidable therein, a firing pin carried by said carrier, a plunger slidable in said housing for engagement with said firing pin, said housing having two non-aligned longitudinal slots, one in advance of the other, and an intermediate cam slot joining said longitudinal

slots, the two longitudinal slots being of different lengths and the one in advance being the shorter slot, a peg projecting from said carrier for movement in said slots, spring means within said housing and normally urging said carrier forwardly relative to said housing, whereby said carrier peg is normally disposed in the shorter advanced slot, the length of this slot being less than the relative longitudinal movement of said housing and said carrier necessary to effect engagement of said plunger and said firing pin.

5. In a tool of the character described, an elongated housing, a carrier slidable therein, a firing pin carried by said carrier, a plunger slidable in said housing for engagement with said firing pin, said housing having two non-aligned longitudinal slots, one in advance of the other, and an intermediate cam slot joining said longitudinal slots, the two longitudinal slots being of different lengths and the one in advance being the shorter slot, a peg projecting from said carrier for movement in said slots, spring means within said housing and normally urging said carrier forwardly relative to said housing, whereby said carrier peg is normally disposed in the shorter advanced slot, the length of this slot being less than the relative longitudinal movement of said housing and said carrier necessary to effect engagement of said plunger and said firing pin, and a sleeve nonrotatably and slidably mounted on said housing and operatively associated with said plunger for effecting forward movement thereof toward said firing pin, said sleeve being

provided with a longitudinal slot into which said carrier peg extends, whereby said peg can be moved into the longer longitudinal slot of the housing by turning said sleeve relative to said carrier.

5. In a tool of the character described, an elongated housing, a carrier slidable in said housing, a firing pin carried by said carrier, a barrel slidable in said housing and detachably secured to said carrier, and a plunger slidable in said housing for engagement with said firing pin, said barrel normally projecting from the front end of said housing and being provided at its front end with means for gripping a surface with which it is brought into engagement in the use of the tool.

6. In a tool of the character described, an elongated housing, a carrier in said housing, a barrel carried by said carrier and normally projecting beyond said housing, said carrier and said housing having limited longitudinal movement relative to one another, a firing pin carried by said carrier, a plunger in said housing for engagement with said firing pin, said plunger and said housing having limited longitudinal movement relative to one another, and resilient means for normally maintaining said firing pin and said plunger separated a greater distance than the extent to which said barrel normally projects beyond said housing, with the result that there must be both relative longitudinal movement of said carrier and said housing and relative longitudinal movement of said housing and said plunger to bring about engagement of said plunger and said firing pin.

7. In a tool of the character described, an elongated housing, a carrier in said housing, a barrel carried by said carrier, said carrier and said housing having limited longitudinal slidable movement relative to one another, a firing pin carried by said carrier, spring means for normally urging said carrier toward the front end of said housing and thereby causing said barrel to normally project beyond the front end of said housing, a plunger in said housing for engagement with said firing pin, said plunger and said housing having limited longitudinal slidable movement relative to one another, and spring means for normally urging said plunger toward the rear end of said housing, said plunger and said firing pin being normally separated a greater distance than the extent to which said barrel normally projects beyond the front end of said housing, with the result that there must be both relative longitudinal movement of said carrier and said housing and relative longitudinal movement of said housing and said plunger to bring about engagement of said plunger and said firing pin.

8. In a tool of the character described, an elongated housing, a carrier in said housing, a barrel carried by said carrier, said carrier and said housing having limited longitudinal slidable movement relative to one another, a firing pin carried by said carrier, spring means for normally urging said carrier toward the front end of said housing and thereby causing said barrel to normally project beyond the front end of said

housing, a plunger in said housing for engagement with said firing pin, said plunger and said housing having limited longitudinal slidable movement relative to one another, and spring means for normally urging said plunger toward the rear end of said housing, said plunger and said firing pin being normally separated a greater distance than the extent to which said barrel normally projects beyond the front end of said housing, with the result that there must be both relative longitudinal movement of said carrier and said housing and relative longitudinal movement of said housing and said plunger to bring about engagement of said plunger and said firing pin said two spring means being disposed on opposite sides of and bearing against a fixed abutment with which said housing is provided.

9. In a tool of the character described, an elongated housing, a carrier in said housing, a barrel carried by said carrier and normally projecting beyond said housing, said carrier and said housing having limited longitudinal movement relative to one another, a firing pin carried by said carrier, a plunger in said housing for engagement with said firing pin, said plunger and said housing having limited longitudinal movement relative to one another, resilient means for normally maintaining said firing pin and said plunger separated a greater distance than the extent to which said barrel normally projects beyond said housing, with the result that there must be both relative longitudinal movement of said carrier and said housing and relative longitudinal movement of said housing and said plunger to bring about engagement of said plunger and said firing pin and exterior hand hold means telescopically related to said housing and connected to said plunger for unison movement therewith.

10. In a tool of the character described, a firing pin carrier having an axial cavity in the front end portion thereof, a barrel having the major portion of its length disposed within said carrier cavity with the side wall of such portion of the barrel in contact with the carrier wall and re-enforced thereby, the front end portion of said barrel projecting beyond the front end portion of said carrier, and means for detachably securing said barrel to said carrier, said means comprising internal threads on the carrier at the front end thereof and cooperating external threads on said barrel intermediate the ends thereof.

STANLEY ALBERT TEMPLE.
